[57] CLAIM

The ornamental design for a vanity case, as shown and described.

DESCRIPTION

FIG. 1 is a perspective view of a vanity case showing
my new design;

FIG. 2 is an inverted bottom rear perspective view
thereof;

FIG. 3 is a perspective view of FIG. 1 with the cover in an open position;

FIG. 4 is a perspective view thereof with the inner compartment lid open; and

FIG. 5 is a perspective view of the vanity case with the cover and mirror in an alternate position.
